US00D530514S

(12) **United States Design Patent** (10) **Patent No.:** **US D530,514 S**
Hernandez et al. (45) **Date of Patent:** **** Oct. 24, 2006**

(54) **TOOL CASE APPARATUS**

(75) Inventors: **Hector R. Hernandez**, Fullerton, CA (US); **Don Hart**, Dana Point, CA (US)

(73) Assignee: **Alltrade Tools LLC**, Long Beach, CA (US)

(**) Term: **14 Years**

(21) Appl. No.: **29/256,046**

(22) Filed: **Mar. 15, 2006**

Related U.S. Application Data

(63) Continuation of application No. 29/219,551, filed on Dec. 17, 2004, now Pat. No. Des. 524,540.

(51) **LOC (8) Cl.** **03-01**

(52) **U.S. Cl.** **D3/288; D3/905**

(58) **Field of Classification Search** **D3/276, D3/281–282, 288, 291, 905; D9/420–421; 206/349, 372–373; 312/902**

(57) **CLAIM**

The ornamental design for a tool case apparatus, as shown and described.

DESCRIPTION

FIG. 1 is a perspective view, depicting a tool case apparatus of the present invention;

FIG. 2 is a side view, depicting the tool case apparatus of FIG. 1;

FIG. 3 is a top view, depicting the tool case apparatus of FIG. 1;

FIG. 4 is a front view, depicting the tool case apparatus of FIG. 1;

FIG. 5 is a back view, depicting the tool case apparatus of FIG. 1; and,

FIG. 6 is a bottom view, depicting the tool case apparatus of FIG. 1.

The broken line showing in all figures is for illustrative purposes only and forms no part of the claimed design.

APPLICATION NO. : 29/256046

DATED : October 24, 2006

INVENTOR(S) : Hector R. Hernandez et al.

It is certified that error appears in the above-identified patent and that said Letters Patent is hereby corrected as shown below:

Drawings

Sheet 1 of 3, delete Figs 1 and 2 and insert replacement Figs 1 and 2.

Signed and Sealed this

Twenty-second Day of May, 2007

A handwritten signature in black ink, appearing to read "Jon W. Dudas". The signature is written in a cursive style with a large, stylized "J" and "W".

JON W. DUDAS
Director of the United States Patent and Trademark Office
